UNITED STATES PATENT OFFICE.

WENZEL FRITSCHE, OF PORTLAND, OREGON.

PROCESS OF PRODUCING PRINTING-PLATES.

1,032,890.

Specification of Letters Patent.

Patented July 16, 1912

No Drawing.

Application filed October 5, 1911. Serial No. 652,932.

To all whom it may concern:

Be it known that I, WENZEL FRITSCHE, a subject of the German Empire, residing at Portland, in the county of Multnomah and State of Oregon, have invented new and useful Improvements in Processes of Producing Printing-Plates, of which the following is a specification.

In known processes for producing printing plates in which the developed picture is adapted to print, there is a particular difficulty to be overcome, viz: the picture produced through the developing in the sensitized layer is so influenced from the first coat of the sensitized layer that the produced picture cannot retain the printing ink or again it may consist of a certain number a desideratum that the actinic and developed picture shall be possessed of the capacity of receiving the printing ink. The fat repelling character is removed by different processes for the production of printing plates, as: 1.—The surface of the plates is de-oxidated—*i. e.*, chemically treated. 2.—The sensitized layer is mixed with an acid calculated to strongly act on the plates, the surface of the plates thus acted upon being removed by mechanical grinding of any suitable description. 3.—The actinic and developed plates will be made ready for printing through electro-galvanic treatment.

The object of my present invention is to provide a simple, economical and otherwise advantageous process for producing printing plates of high grade.

In the practice of the invention the actinic printing plates will be exposed under the picture, and then developed. To make the printing plates susceptible for the printing ink, they will be coated with a peculiar fat—*i. e.*, a fat containing an acid bound in ethereal oil. This fatty substance with which the developed printing plates are coated changes the surface of the developed pictures in the sensitized layer in such manner that the printing plates will receive the printing ink without being subjected to a mechanical or a chemical action.

In the carrying out of the process in the best manner of which I am cognizant, the printing plates are first coated with a sensitized layer consisting of glue and bichromate. These coated plates are dried and exposed under the picture, and are then developed in cold water, after which they are

dipped in a one per cent. solution of sodium hydroxid. After being given this bath the plates are thoroughly washed, and are then coated immediately with a fatty substance containing a corrosive—*i. e.*, an ethereal oil with those acids or their salts which are proper for corrections. By this is meant that one design produced on a metal printing plate for lithographic printing is corrected, changed or amplified. For instance the design is increased in one part on the printing plate. This added portion of the design can be drawn on the printing plate with lithographic ink or lithographic pencil, it being important to make the new drawn portion on the printing plate capable of receiving the printing ink before the produced design on the printing plate can be corrected, altered or amplified in its shape or corrected in any manner. The portion of the printing plate in which the changes or corrections are to be made must be chemically treated before the new design or any corrections can be made. The acids and salts for such treatments of printing plates for lithographic prints to make any corrections on produced designs on printing plates are always different according to the kind of metal used in the plates. For instance zinc printing plates are treated for such corrections as mentioned with citric acid or acetic acid, and aluminum printing plates are treated with a thin solution of sulfuric acid. As soon as one portion of a plate is coated with said acid and the acid is dry on the plate, the surface of the plate is so changed and influenced that the corrected portion or new drawn design on the plate is rendered capable of receiving printing ink. These acids and salts are always different according to the metals, and they are well known. Some of the ethereal oils have the property that they combine in certain percentage with acids or their salts. For instance, camphor or oil of cloves is combined with acetic acid in about the proportions stated; viz: camphor or oil of cloves 125 parts and acetic acid 15 parts to 1500 parts of fat or any kind of printing ink. If the mixture of camphor or oil of cloves and acetic acid be added to printing ink and the developed printing plates coated with the mixed fatty substance, the surface of the developed picture will be so affected and influenced that it is well adapted to receive and retain the

printing ink. Thus the printing plates are completed and made ready for printing in one short operation. After coating the printing plates with the mixed fatty substance the surface of the developed picture in the sensitized layer is so affected that the printing plate will receive the printing ink without being subjected to a mechanical or chemical action. Then after said coating and when the thin film of the sensitized layer is removed, the printing plate is adapted to receive any kind of printing ink to print from the plate. The actinic layer upon the plate and which is fat repelling without any etching, can be removed with a thin solution of sulfuric acid, but this is not absolutely necessary.

Having described my invention, what I

claim and desire to secure by Letters Patent, is:

A process of producing photo-mechanic printing plates, which consists in coating the surface of a developed printing plate containing a picture in a sensitized layer, with fat containing an acid bound in ethereal oil; the said fat being adapted to act on the surface of the developed picture to enable the picture in the sensitized layer to retain the printing ink.

In testimony whereof I have hereunto set my hand in presence of two subscribing witnesses.

WENZEL FRITSCHE.
